UNITED STATES PATENT OFFICE

WILLIAM H. H. DAVIS, OF SAN FRANCISCO, CALIFORNIA

PROTECTOR

Application filed December 23, 1929. Serial No. 415,996.

This invention relates generally to apparatus for use in conjunction with a heater for waving hair. It relates particularly to the waving of hair by the croquignole method in which the wound hair is positioned substantially parallel to the scalp.

It is the general object of this invention to provide a method for the waving of hair without having an undesirable sensation of heat occurring upon the scalp during the process and to devise novel means for accomplishing this.

Further objects of this invention will appear in the following description in which I have set forth the preferred embodiment of my invention. It is to be understood that the appended claims are to be accorded a range of equivalents consistent with the state of the prior art.

20 Referring to the drawings:

Figure 1 is a perspective view, illustrating a complete form of apparatus for waving hair, the apparatus embodying my invention.

25 Figure 2 is a plan view of the apparatus without the mandrel.

Figure 3 is a side elevation of the apparatus shown in Figure 2.

30 Figure 4 is an end elevation of the apparatus shown in Figure 3.

Figure 5 is a perspective view, illustrating a step in the assembly of the apparatus.

Figure 6 is a perspective view illustrating another step in the assembly.

35 Figure 7 is a cross section through the assembled apparatus before the heater is positioned.

Figure 8 is a perspective view of a clip employed with the apparatus.

40 Figure 9 is a perspective of the protector of my invention joined to the clip shown in Figure 8.

This invention may be characterized briefly as comprising the waving of hair in such a manner that the transmission of heat to the scalp is minimized and reduced to such an extent that the sensation of heat adjacent the scalp is overcome. While the apparatuses utilized heretofore have overcome 45 this sensation by the use of protectors to

some extent it has not been overcome substantially entirely. In accordance with my invention I provide means for reducing the transmission of heat to the scalp to such a degree as practically obviates the sensation. 55 This means may be employed with any of the convenient form of apparatuses utilized in waving hair.

In that type of apparatus which I have shown in the drawings, a protector 9 includes clamping means formed by elongated members 11, hingedly secured together at 12, and adapted to be locked together by locking means indicated generally at 13. The elongated members 11 are usually formed 60 of metallic strips bent to provide curved U-shaped sections 16 in which are positioned strips 17 of a resilient material as soft vulcanized rubber. To reduce in some degree the transmission of heat to the scalp, the 65 metallic strips are preferably faced with wood strips 18 to which they are secured by pins 19. The lower faces of the wood strips are covered with lengths 21 of felt or other equivalent soft material. 70

The locking means 13 conveniently comprises a locking lever 22 carried by one of the metallic strips 11 and adapted to slip over projecting end 23 of the opposed metallic strip 11. Cam lever 24 pivoted upon the 75 locking lever is adapted to contact with the cooperatively formed projection 23 and to be moved as shown in Figures 2 and 6 to lock the respective members in hair clamping position.

To provide for the heating of the hair in wound form I preferably employ the clamping means with a mandrel or spindle 26 upon which the hair can be wound. This mandrel is preferably substantially circular in cross section and has an intermediate portion 27 of reduced diameter. Lug 28 extending from one end of the mandrel provides convenient means for its rotation by an operator while the ratchet teeth 36 are 95 adapted to cooperate with a ratchet or pawl 37 carried by the clamping apparatus as will presently be explained.

To position the mandrel on the protector 9 I provide upstanding support members 38 100

and 39. Support member 38, suitably apertured to receive the lug end of the mandrel, is formed integrally with a plate 41 provided upon and spaced from the metallic strip. The locking lever is provided with a supporting end 42 adapted to cooperate with the support member 39 which extends from plate 41 to form support means for the other end of the mandrel. The pawl 37 is secured to the upper plate 41 adjacent the member 39 and is cooperatively arranged with teeth 36 to prevent rotation of the mandrel in one direction.

A second upper plate 44 is secured to the metallic strip 11. This plate 44 is curved to form a guide lip 46 over which the hair extends and which prevents it being cut.

In utilizing my apparatus, a comparatively wide strand of hair is first placed between the members 11, when these members are separated as shown in Figure 5. The members are then brought together and clamped in position upon the strand of hair by the locking means 13, the members then being practically parallel to the scalp. As is shown in Figure 6, the engaged strand of hair is wound upon the mandrel 26, the mandrel then being seated upon the support members 38, 39 and 42. As the hair is wound upon the mandrel and positioned in the several support members, ratchet 36 engages the pawl 37. As the mandrel is seated in the supporting members, additional rotation of the mandrel by the operator serves to tension the hair while the pawl 37 ratchets over the teeth 36. The engagement of the pawl preserves the tension in the wound hair when finally positioned in the support members.

It has been my observation that the sensation of heat on the scalp is due in large measure to the passage of heat and of vapors arising from the liquid used on the hair during the waving down through the space between the members and also down along the strand of hair to the scalp. This has occurred even though rubber liners have been used to grip the strand of hair.

In accordance with my invention I provide means for use in connection with the hair waving appliance for minimizing this sensation of heat upon the scalp. This is accomplished by providing a sheet of proper material which is positioned with the other apparatus in such a manner as to extend beneath the wound spindle. A material which gives good results is felt, which serves as a heat insulator and as an absorber of vapors. The felt is usually in the form of a strip or sheet 47.

The hair is wound about the mandrel or spindle, the felt strip being wound in with it so that when the mandrel is finally positioned upon the supporting members, the felt extends about the mandrel contiguous to

the hair and across the members as is shown in Figure 7. When the heating element, designated generally at 48, is positioned about the mandrel to heat the hair, a sheet 49 of waxed paper being interposed between them, until it sets into the desired wave, the sensation of heat upon the scalp is substantially prevented by the presence of the felt strip which extends contiguous to the wound hair and across the space left unoccupied by the strand of hair between the elongated members 11, so that heat and hot vapors do not pass down to the scalp. Further, when vaporizable liquids such as oil or water are employed during the heating of the hair, the felt absorbs and so prevents the passage of heated vapors to the scalp, or adjacent to the scalp, thus obviating the sensation of heat.

To facilitate positioning of the felt I have employed means for securing it on the protector 9. A form of such means is illustrated by a clip 51 which is constructed of sheet metal to have prongs 52 for extension between the metallic strip 11 and the plate 41. The clip is conveniently joined to the felt strip by crimping an edge 53 over to engage the felt.

I claim:

1. In a hair waving appliance, a pair of elongated members, means for clamping opposed edges of said members together in proximity to the scalp with a strand of hair extended between the same, means for holding the hair in wound form in proximity to said members, and means wound with the hair and overlying the space between said members for substantially preventing vapors from passing between said members to the scalp.

2. In a hair waving appliance, a pair of elongated members, means for clamping opposed edges of said members together in proximity to the scalp with hair extended between the same, means for holding hair in wound form in proximity to said members, and a flexible sheet positioned adjacent and extending across said members for substantially preventing heat and vapors from passing to the scalp.

3. In a hair waving appliance, a pair of elongated members, means for clamping opposed edges of said members together in proximity to the scalp with hair extended between the same, means for holding hair in wound form in proximity to said members, and a sheet of absorbent material wound with the hair and extending across the members to substantially prevent heat and vapors from passing to the scalp.

4. In a hair waving appliance, means for holding a strand of hair in wound form parallel to the scalp, means for heating the hair, and a flexible sheet of substantially poor heat conducting material wound with the

hair and underlying the first mentioned means for preventing heat and vapors from passing to the scalp.

5. In a hair waving appliance, means for holding a strand of hair in wound form parallel to the scalp, and a flexible sheet of material wound with a turn of the hair and held with and completely underlying it.

10. In a hair waving apparatus, a spindle upon which a strand of hair is adapted to be wound in such a manner that the spindle is finally positioned adjacent to and with its axis substantially parallel to the adjacent portion of the scalp, a sheet of flexible material wound into a coil of the hair on the spindle and arranged to normally extend beneath and completely underlie the spindle when the spindle is in said final position, and means for heating the wound 15 hair.

20. 7. A device for use with a hair waving apparatus including a spindle upon which a strand of hair is adapted to be wound in such a manner that the spindle is finally 25 positioned adjacent to and with its axis substantially parallel to the adjacent portion of the scalp, the device comprising a sheet of flexible material adapted to be wound into a coil of the hair and arranged to completely underlie the spindle when the spindle 30 is in said final position.

8. A device for use with a hair waving apparatus including a spindle upon which a strand of hair is adapted to be wound in 35 such a manner that the spindle is finally positioned adjacent to and with its axis substantially parallel to the adjacent portion of the scalp, the device consisting of a sheet of flexible absorbent and non-heat conducting material adapted to be wound into a coil 40 of the hair and arranged to completely underlie the spindle when the spindle is in said final position.

45. 9. In a hair waving appliance, a pair of clamping members adapted to retain a strand of hair therebetween, a mandrel supported above said members and upon which the strand of hair is adapted to be wound, and a flexible sheet secured to one of said 50 members and adapted to be wound with the hair in the direction of the other of said members beneath said mandrel.

In testimony whereof, I have hereunto set my hand.

55. WILLIAM H. H. DAVIS.
